UNITED STATES PATENT OFFICE.

RANDLE P. YOCOM, OF CHEBANSE, ILLINOIS.

MAIL-CARRIER.

No. 879,125.

Specification of Letters Patent.

Patented Feb. 11, 1908.

Application filed July 25, 1907. Serial No. 385,564.

To all whom it may concern:

Be it known that I, RANDLE P. YOCOM, citizen of the United States, residing at Chebanse, in the county of Iroquois and State of Illinois, have invented certain new and useful Improvements in Mail-Carriers, of which the following is a specification.

The present invention relates to certain new and useful improvements in mail carriers of that type which are utilized in connection with rural mail delivery routes for transporting mail between the house and the point where the mail is deposited.

The object of the invention is to design a mail carrier comprising a car suspended from and mounted upon a track, novel means being utilized for mounting the car and operating the same.

For a full description of the invention and the merits thereof and also to acquire a knowledge of the details of construction and the means for effecting the result, reference is to be had to the following description and accompanying drawings, in which:

Figure 1 is a perspective view of the improved mail carrier. Fig. 2 is a plan view of the frame at one end of the mail carrier. Fig. 3 is an enlarged view of the upper portion of the intermediate standard. Fig. 4 is a similar view of the end post. Fig. 5 is a vertical transverse sectional view through the car. Fig. 6 is an enlarged view of the upper portion of one of the hangers upon the car.

Corresponding and like parts are referred to in the following description and indicated in all the views of the drawings by the same reference characters.

In general a mail carrier constructed in accordance with the invention comprises an over head track, a car suspended from the track, and an endless operating cable for moving the car back and forth upon the track. The track 1 extends from the highway or point where the mail is delivered to the house and in the present instance is shown as in the nature of an ordinary wire. A post or other support 2 is located at the delivery end of the mail carrier and has a bracket 3 secured thereto, the said bracket supporting one end of the track 1 and being formed with a pendant arm 4 upon which a pulley 5 is journaled. An upright frame is located at the opposite end of the mail carrier and comprises the vertical sides 6 having the extremities thereof connected by the cross bars 7. A transverse

member 8 also connects the sides 6 at an intermediate point and supports an end of the track 1. A vertical bar 9 connects the two ends of the frame and is slightly spaced from one of the sides 6, a shaft 10 being journaled between the bar 9 and the opposite side 6 and having a pulley 11 keyed thereon. This shaft 10 also carries a pinion 12 located between the vertical bar and the adjacent side 6 and meshing with a gear wheel 13 also mounted between the vertical bar 9 and the adjacent side of the frame. The shaft upon which the gear wheel 13 is keyed projects outwardly beyond the frame and is provided with a crank handle 14 by means of which the pulley 11 can be conveniently rotated.

Standards 15 are located at intermediate points upon the mail carrier and carry brackets 16 having the ends thereof extended upwardly and secured to the lower side of the track 1. The upwardly extending ends of the bracket 16 are formed with inclined offset portions 17 and have guide wheels 18 journaled thereon. For the purpose of cooperating with the inclined offset portion 17 of the brackets to guide a cable into engagement with the guide wheel, the brackets carry guide members 19 which are inclined outwardly in an opposite direction. Pendent from the brackets 16 are the pulleys or guide members 20.

The car for transporting the mail comprises a receptacle 21 and a frame for supporting the receptacle. The receptacle is shown as of an elongated formation and as provided at one end with a hinged closure 22 which may be of any approved construction. The frame for supporting the receptacle comprises a pair of upright hangers 23 rigidly connected by bracing 24 and having their lower ends bent around the receptacle as indicated at 25 while the upper ends are returned and carry the grooved wheels 26 engaging the track 1. For the purpose of moving the car back and forth upon the track an endless operating cable 27 is utilized which is secured to the car and passes around the pulley 5 upon the post 2 and the pulley 11 operated through the medium of the crank handle 14. The upper portion of the endless operating cable 27 is designed to pass over the guide wheels 18 whereas the lower portion engages the pulley 20, such arrangement reducing the friction and preventing any binding of the various members.

With the foregoing construction it will be

readily apparent that by operating the crank handle 14 and turning the pulley 11 movement will be imparted to the car through the medium of the operating cable 27 and the said car can be thus moved back and forth between the mail delivery point and the residence of the operator.

Having thus described the invention, what is claimed as new is:

- 10 1. In a device of the character described, the combination of a track, standards, brackets carried by the standards and provided with upwardly extending end portions supporting the track, a car mounted upon the track, a guide wheel mounted upon the upwardly extending portion of the bracket, an operating cable for the car designed to engage the guide wheel, and a guide carried by the bracket for leading the cable into engagement with the guide wheel.
- 15 2. In a device of the character described, the combination of a track, standards, brackets carried by the standards and provided with upwardly extending end portions engaging the track, the said end portions being formed with inclined offset portions, a car mounted upon the track, a guide wheel mounted upon the upturned end of the bracket, an operating cable for moving the
- 20 car, the said cable being designed to engage the guide wheel, and a guide member coöperating with the inclined offset of the bracket to lead the cable into engagement with the guide wheel.
- 25 3. In a device of the character described, the combination of a track, standards,

brackets carried by the standards and provided with upturned ends engaging the track, the said upturned ends being formed with inclined offsets, a car mounted upon the track, 40 a guide wheel mounted upon the upturned end of the bracket, an endless operating cable for moving the car, a guide member coöperating with the inclined offset of the bracket to hold the upper portion of the cable in engagement with the guide wheel, and a pulley pendent from the bracket for engaging the lower portion of the cable.

4. In a device of the character described, the combination of a track, means for supporting the track, a car mounted upon the track, a frame at one end of the track comprising side pieces, a bar spaced from one of the side pieces, a shaft journaled between the said bar and opposite side piece and projecting into the space between the bar and adjacent side piece, a pulley rigid with the shaft, a pinion rigid with the shaft and located in the space between the bar and the adjacent side piece of the frame, a gear 55 wheel meshing with the pinion and also mounted between the bar and adjacent side piece of the frame, means for operating the gear wheel, and an endless operating cable for the car, the said cable passing around the 60 pulley.

In testimony whereof I affix my signature in presence of two witnesses.
